HILLSIDE PLOW.

No. 399,001.

Patented Mar. 5, 1889.

UNITED STATES PATENT OFFICE.

MILO D. BEACH, OF LITCHFIELD, CONNECTICUT.

HILLSIDE-PLOW.

SPECIFICATION forming part of Letters Patent No. 399,001, dated March 5, 1889.

Application filed November 16, 1888. Serial No. 291,026. (No model.)

To all whom it may concern:

Be it known that I, MILO D. BEACH, a citizen of the United States, residing at Litchfield, in the county of Litchfield and State of Connecticut, have invented certain new and useful Improvements in Hillside-Plows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to plows; and it consists in certain improvements in swivel or hillside plows, as hereinafter set forth and claimed. In a separate application filed herewith I have described certain devices by 20 means of which the jointer or colter and the clevis of an iron-beam swivel-plow can be automatically reversed by the movement of the duplex hook when the mold-board is reversed. In this application I propose to show how a 25 similar result can be effected with a wooden-beam plow. I also show and describe an improvement in shifting handles, this latter being applicable to either wooden or metal beams.

30 In the drawings, Figure 1 is a side elevation, partly broken away, of a wooden-beam plow embodying my improvements. Fig. 2 is a plan of the casting containing the bearing for the jointer or colter stem. Fig. 3 is a plan of the clevis end of the beam. Fig. 4 is an end view of the casting attached to the end of the plow-beam. Fig. 5 is a plan of the shifting handles, partly broken away. Fig. 6 is a plan of the bearing between the handles and the 35 standard. Fig. 7 shows the boxes. Fig. 8 is a side elevation showing the journals. Fig. 9 is a plan of the head for the adjustable crank-pin. Fig. 10 is a cross-section of the rack. Fig. 11 is a side view of a modification of the 40 jointer-stem bearing. Figs. 12 and 13 show the double eccentric for this bearing.

The same reference-letters are used in all the figures.

45 The wooden beam A is provided with the standard A', attached to it in the ordinary

manner. In the under side of the beam is cut a longitudinal groove to receive the shaft B B', which runs from the rear end of the beam to a point near the clevis. It is provided with suitable attachments for reversing the position of the jointer or colter and the clevis, as hereinafter explained. It receives its motion through a bevel-gear, C, secured to its rear end, with which meshes a curved rack, D, formed in or attached to the bar D', which 55 unites the handles E. The duplex hook F, which locks the swiveling mold-board in either of its positions, is pivoted to the bar D' by the vertical bolt f. The handles can be shifted laterally to enable the plowman to 60 walk in the furrow, and their movement from one side to the other rotates the shaft B and operates the jointer or colter and the clevis. The ends of the handles E are bolted to the two blocks G by means of the bolt e, which 65 passes through a slot, a, in the web of the standard, and also through slots g in the blocks. Above and below the slot a are parallel slots a' a', the material a² between them being cylindrical in shape. At each end of 70 the blocks G is a semicircular bearing formed between two projecting jaws, g', which are adapted to enter the slots a' a', and thereby receive the journals a² in their bearings. The jaws on the two blocks abut, as shown in 75 Fig. 6, and the bolt e holds them firmly together. The bar D', to which the handles are fastened, has a semicircular groove, d, in its front edge below the rack D. The groove fits a rounded flange, A², projecting rearwardly 80 from the standard A', so that the bar D' can slide laterally on the flange A². The handles are therefore supported on the journals a² and the flange A². By adjusting the bolt e up or down in the slots a and g the frontends 85 of the handles will be raised or lowered, the flange A² serving as the fulcrum on which the handles move. This permits the rear ends of the handles to be adjusted vertically to suit the plowman without interfering with their 90 capacity for shifting laterally. In front of the standard A' there is bolted to the under side of the beam a casting, H, which contains a tubular bearing, H', for the stem I of the jointer or colter. This casting has a base- 95 100

plate, h , provided with perforated ears h' , to receive the bolts, and a rear extension, h^2 , to give it sufficient bearing against the beam. The tubular bearing H' has a hollow rib, h^3 , 5 projecting from its front, to receive the upper part of the blade of the colter, as fully set forth in my other application aforesaid. A brace, h^4 , runs from the lower end of the tubular bearing back to the rear extension, h^2 , of 10 the base-plate.

The beam A above the tubular bearing is recessed out to receive the double eccentric J, which has at each end a hub containing a square socket to fit the squared ends of the 15 shaft B B'. The hubs are joined by the short straight cylindrical shaft J, whose axial line crosses that of the shaft at an angle about midway between the hubs at the point where it is intersected by the axis of the stem 20 I. It thus constitutes a double crank or double eccentric, and by engaging with the diametrical slot in the top of the jointer or colter stem it operates to oscillate said stem on its axis when the shaft B B' is rotated. The 25 casting H is provided with a pocket, h^5 , into which the tubular bearing H' opens, and which, taken in connection with the recess in the beam A, forms a chamber, in which the eccentric J can revolve.

30 The clevis end of the beam A is protected and strengthened by a box-shaped casting, K, having a top and bottom and a front end. Integral with the bottom and end is an open cylindrical tube, k , which forms a bearing 35 for the stem L. The casting K is secured to the beam by suitable bolts, as shown. In the inner end of the stem is a square cavity, into which fits the squared end of the shaft B'. The front edge of the head L' is curved and 40 is provided with a T-shaped flange, l , formed by a groove, l' , cut in each face parallel with the front edge. A dog, M, having a set-screw, m , slides on the flange l and is provided with a nose or pin, M', engaging with 45 a vertical groove in the inside of the clevis O. The arms o of the clevis are hooked to engage with the headed studs L², projecting from the top and bottom of the casting K. The hooks are open, as shown, to permit the 50 clevis to be disengaged from the studs when swung around at right angles to the beam.

The operation of the head L', the adjustable dog M, the clevis O, and the clevis-hook P are the same as described in my other application and need not be detailed here. The 55 top and bottom of the casting K have lugs k' formed thereon, between which are held the standards Q of the wheel.

Figs. 5 and 8 show how the shifting handles can be applied to a plow similar to that shown in my other application, and having an upwardly-extending shaft, B², stepped in a bearing, a^3 , on the standard. The connection of the duplex hook and its axially-yielding bolt is the same as set forth in that application.

Figs. 11, 12, and 13 show a mode of forming the bearing for the jointer or colter stem in a straight metal beam. The bearing is cast integral with the beam, in the web of 70 which is formed an opening, A³, to permit the eccentric J to revolve. The stem of the jointer or colter has a bearing above the opening A³, and the upper and lower ends of the slot through it are indicated by dotted lines 75 in Fig. 11. In order to get the eccentric J into place, its socket j and the part j' are made of the same width as the diameter of the shaft, so that it can be passed through the narrow slot in the stem, the latter being 80 turned until its slot stands transversely to the beam. When the shoulders of the cylindrical hub j^2 strike the stem, it is turned back to bring the hub into line with the bearing A⁴, into which it is slid. The shaft B can 85 then be slipped into the socket j and secured thereto.

Instead of using shifting handles with the plow shown in Fig. 1, I may use stationary handles, and operate the bevel-gear C by 90 means of a sector-gear attached to the hub of a duplex hook, as shown and described in my other application.

Having thus described my invention, what I claim, and desire to secure by Letters Patent, 95 is—

1. The combination, with a plow-standard, A', having a rounded flange, A², of the vertically-adjustable handles E, secured to the bar D', which has a groove, d, fitting the flange 100 A², substantially as described.

2. The combination, with a plow-standard having the slot a and the journals a², of the handles E, the blocks G, having the slots g, and bearings for the journals a², and the bolt 105 e, passing through the slots a and g and adjustably securing the handles to the blocks, substantially as described.

3. The combination, with a plow having a reversible jointer or colter, of a shaft provided with crank-like devices for actuating the jointer or colter, a gear-wheel on said shaft, a pair of laterally-shifting handles, and a rack fastened to the handles and meshing with the gear-wheel, substantially as described.

4. The combination, with a plow having a laterally-swinging clevis, of a shaft provided with a crank-pin for actuating the clevis, a gear-wheel on said shaft, a pair of laterally-shifting handles, and a rack fastened to the handles and meshing with the gear-wheel, substantially as described.

5. The casting H, having a tubular bearing, H', a base-plate, h , ears h' , rear extension, h^2 , 115 hollow rib h^3 , and brace h^4 , adapted to be attached to a plow-beam and receive the stem of a jointer or colter, substantially as described.

6. The casting K, having a top, bottom, and end, and a tubular bearing, k , adapted to be attached to the end of a plow-beam and afford

a bearing for the shaft, substantially as described.

7. The casting K, having a top, bottom, and front end, tubular bearing k , and lugs k' , adapted to be attached to the end of a plow-beam and receive the wheel-standards, substantially as described.

In testimony whereof I affix my signature in presence of two witnesses.

MILO D. BEACH.
